[57] **CLAIM**

The ornamental design for a chandelier, as shown and
described.

DESCRIPTION

FIG. 1 is a perspective view of a chandelier showing
my new design;

FIG. 2 is a front elevational view of the chandelier, the
rear elevational view being identical;

FIG. 3 is a right side elevational view of the chandelier,
the left side elevation view being identical;

FIG. 4 is a top plan view of the chandelier; and,

FIG. 5 is a bottom plan view of the chandelier.

Light bulbs are shown in broken lines for illustrative
purposes only and form no part of the invention.
